UNITED STATES PATENT OFFICE.

FRANCIS H. MATTHEW, MARTIN A. BROADBEE, AND FREDERICK C. B. VOSGERAU,
OF VENICE, CALIFORNIA; SAID VOSGERAU ASSIGNOR OF HIS RIGHT TO LLOYD H.
BARKNECHT, OF VENICE, CALIFORNIA.

CURRENT-CONDUCTING APPARATUS.

Application filed July 16, 1924, Serial No. 726,365. Renewed March 12, 1928.

Our invention relates to ignition systems for internal combustion engines, and more particularly to means for conducting the current from the spark coil to the several spark 5 plugs of the engine.

It is a purpose of our invention to provide an apparatus by which the spark coil, distributor and conductors from the distributor to the spark plugs are thoroughly insulated 10 and thus protected against oil, grease and water to permanently prevent short circuits and current leaks, thereby producing an ignition system in which the maximum current which the system is capable of generating will 15 at all times be supplied to the spark plugs.

It is also a purpose of our invention to provide a current conducting apparatus having connectors which are extensible to provide electrical connections between the spark plugs 20 and a stationary part of the apparatus, and collapsible to permit the ready disconnection of the apparatus from the plugs when it is desired to remove the plugs for cleaning or 25 other purposes.

We will describe only one form of current conducting apparatus embodying our invention, and will then point out the novel features thereof in claims.

In the accompanying drawings

Figure 1 is a view showing in top plan one 30 form of current conducting apparatus embodying our invention in applied position with respect to an internal combustion engine;

Figure 2 is an enlarged vertical sectional view taken on the line 2—2 of Figure 1;

Figure 3 is a similar view taken on the line 35 3—3 of Figure 1; and

Figure 4 is a horizontal sectional view 40 taken on the line 4—4 of Figure 3.

Referring specifically to the drawings, in which similar reference characters refer to similar parts, our invention in its present embodiment comprises a conduit K of suitable 45 insulating material, such as bakelite, and of suitable length and diameter to properly perform the functions for which it is designed.

This conduit K is rigidly held at one side of 50 an internal combustion engine, designated at E, by means of a pair of brackets B which, as shown, are secured to the cylinder head and in embracing relation to the conduit so that the latter is fixedly secured against vibration.

As shown in Figures 1 and 2, the conduit 55 has embedded therein conductors 15 in the form of wires which extend longitudinally through the conduit to various points along the length of the conduit for connection with conducting rings 16 also embedded in the 60 conduit and having portions exposed to the periphery of the conduit through openings 17. The inner ends of the conductors 15 are extended into a housing H also formed of insulating material, and preferably 65 molded integral with the conduit K. As illustrated to advantage in Figure 3, the housing is of tubular form, with its opposite ends open, and a partition 18 also formed of insulating material divides the housing 70 interiorly into an upper compartment 19 and a lower compartment 20. The compartment 19 is adapted to receive a conventional spark coil 21 which is completely housed through the provision of a cover 22 threadedly engaging the housing and having extending therethrough a binding post 23 to which a conductor 24 is connected, which leads to the battery, 75 as will be understood. The post 23 has electrical connection with the primary winding 80 of the coil and the secondary is adapted for electrical connection to a rotating contact (not shown) of a distributor D. The distributor D is received within the lower compartment 20, and a conductor 25 extends 85 through the partition 18 for connecting the secondary to the rotating contact. This distributor D is rotatably mounted in the compartment 20 and is guided in its movement by a plurality of headed pins 26 movable in 90 slotted plates 27 embedded in the partition 18. The pins are received in sockets 28 formed on the casing of the distributor so that upon rotation of the distributor through the conventional mechanism the pins will 95 slide within the arcuate slotted plates. To each plate 27 is connected a conductor 15, it being understood that the four conductors 15 are connected to the respective plates 27 so as to receive the current distributed from the 100 distributor.

By reference to Figures 1 and 2, it will be seen that a plurality of connectors, designated generally at G, extend laterally from one side of the conduit K, there being one connector for each of the several spark plugs of the internal combustion engine. In the present instance, as we have shown a four cylinder

engine, four connectors are provided, and each connector includes a male member 29 telescopically associated with a female member 30, the two being formed of insulating material as indicated. The male member 29 has embedded therein a conducting rod 31, one end of which is provided with a disk shaped head 32 which is disposed within the female member 30 to provide an abutment 10 for a coiled expansible spring 33. The end of the female member 30 is closed by a head 34 threadedly fitted on the member and formed of conducting material. A V-shaped ear 35 constitutes a part of the head 34 and is adapted to receive the binding post 36 of the spark plug and is adapted to be gripped by the binding nut 37, as will be understood. The spring 33 is interposed between the heads 32 and 34 and operates to normally urge the 20 members 29 and 30 in opposite directions, as will be understood. The outer end of the member 29 is provided with an arcuate head 38 and projecting from this head is the opposite end of the conducting rod 31. The arcuate head 38 is adapted to conform to the peripheral curvature of the conduit K and the rod 31 is adapted to extend through the opening 17 for electrical contact with the ring 16.

In the application of a connector to the conduit K the members 29 and 30 can be forced inwardly toward each other and against the action of the spring 33 to permit the insertion of the connector between the conduit and the respective spark plug when, after positioning the connector so that the conducting rod 31 has electrical contact with the corresponding conducting ring 16, the members are released, thereby permitting the spring to expand the members, with the member 29 forced against the conduit and the head 34 of the member 30 forced against the binding post 36. In this manner the connector is rigidly maintained in spanning position with respect to the conduit and spark plug, and when the nut 37 is in applied position the connector is firmly locked against accidental displacement.

In practice, the conductors 15 and 16, as well as the conducting rods 31, are adapted 50 to be embedded in the respective elements during the molding thereof so as to provide thorough and permanent insulating means therefor, and effectively protecting the several conductors against short circuits and 55 current leakages. With the spark coil 21 and the distributor D in position within the housing H it will be clear that current can be supplied to the several spark plugs of the motor through the following circuits: from 60 the pins 26 of the distributor through the plates 27, conductors 15, and conducting rings 16, conducting rods 31, springs 33 and heads 65 34 to binding post 36. Should it be desired to remove any one of the spark plugs, it will be clear that it is only necessary to force the

corresponding female member 30 in the direction of the conduit K sufficiently to disengage the ear 35 from the binding post 36, when the entire connector can be disengaged from the spark plug. 70

It is to be noted that none of the conductors 15 cross each other within the conduit K, thereby eliminating any possibility of short circuiting. This is rendered possible by virtue of the provision of the ring conductor 16, as it will be manifest that the conductors 15 can be extended straight through the conduit at different points along the length of the latter and into electrical contact with their respective rings 16. An electrical conducting apparatus comprising a solid conduit of insulating material, conducting wires embedded therein, and ring conductors embedded in the conduit and having electrical contact with the wires, the arrangement of wires being such that one wire is connected to one ring conductor and the several wires connected to the conductors at different points to prevent crossing of the wires. 80 85 90

Although we have herein shown and described only one form of current conducting apparatus embodying our invention, it is to be understood that various changes and modifications may be made herein without departing from the spirit of the invention and the spirit and scope of the appended claims. 95

We claim:

1. A current conducting apparatus for the ignition systems of engines comprising a solid conduit of insulating material, a housing of insulating material formed integral with the conduit and adapted for receiving a spark coil and a distributor, conductors connected to the distributor and embedded in the conduit, and connectors detachably associated with the conduit and adapted for detachable connection to spark plugs for conducting current from the conductors to the spark plugs. 100 105 110

2. A current conducting apparatus as embodied in claim 1, wherein the connectors are provided with coverings of insulating material. 115

3. A current conducting apparatus for the ignition systems of engines comprising a solid conduit of insulating material, a housing of insulating material formed integral with the conduit adapted for receiving a spark coil, a distributor, conductors connected to the distributor and embedded in the conduit, and telescopic connectors detachably associated with the conduit and adapted for detachable connection to spark plugs for conducting current from the conductors to the spark plugs and connecting means for the conductors and connectors. 120 125 130

4. A current conducting apparatus for the ignition systems of engines, comprising a solid conduit of insulating material, conduc-

tors embedded therein, and telescopic connectors having coverings of insulating material and comprising male and female members and means for urging the members in opposite directions, said connectors having electrical connection with the conductors.

5. A current conducting apparatus for ignition systems of engines, comprising a solid conduit of insulating material, a housing of insulating material formed integral therewith, a partition in the housing for dividing the latter into two compartments, one adapted for the reception of a spark coil and the other for the reception of a distributor and conducting plates embedded in the partition.

6. An electric conducting apparatus comprising a solid conduit of insulating material, a housing integral therewith, a partition in the housing for dividing the latter into two compartments, one adapted for the reception of a spark coil and the other compartment having means for receiving and centering a distributor therein.

7. A current conducting apparatus for the ignition systems of engines comprising a conduit of insulating material adapted to be fixedly secured to the engine, telescoping conducting members adapted to connect the conduit to the spark plug of an engine, insulating means for the telescoping members, and a resilient member interposed between the two for normally expanding the same.

8. A current conducting apparatus for ig-

nition systems of engines, comprising a conduit of insulating material rigidly connected to the engine, conducting rings and conductors connected together in the conduit, telescopic connecting members adapted to connect the conduit with the spark plug of the engine, connecting rods secured to the rings, means interposed between the telescopic members for normally expanding the same, and means for insulating the telescopic members and rings and connectors.

9. A current distributing apparatus for the ignition systems of engines, comprising a solid conduit of insulating material, a housing of insulating material formed integral with the conduit and having a pair of compartments, one adapted for the reception of a spark coil and the other for the reception of a distributor, conductors embedded in the conduit and extending into the compartments of the housing, and current conducting means connected to the conductors adapted for conducting current from the conductors to the spark plugs of an engine.

10. A current conducting apparatus as embodied in claim 9, wherein one of the housing compartments is adapted to receive a spark coil through the top and the other compartment is adapted to receive a distributor through the bottom thereof.
